(57) **CLAIM**

The ornamental design for a combined athletic shooting aid and training device, substantially as shown and described.

DESCRIPTION

FIG. 1 is a front isometric view of a combined athletic shooting aid and training device according to the invention showing the new design installed in a surface mounted goal, indicated by the phantom lines which are not a part of the invention;

FIG. 2 is a rear isometric view thereof;

FIG. 3 is a front elevational view thereof;

FIG. 4 is a right side elevational view, left side view being

an identical mirror image thereof;

FIG. 5 is a top plan view thereof;

FIG. 6 is a bottom plan view thereof; and,

FIG. 7 is a rear elevational view thereof.
